UNITED STATES PATENT OFFICE.

EDWIN E. SLICK, OF PITTSBURG, PENNSYLVANIA.

METHOD OF ROLLING FLANGED SHAPES.

No. 852,985.

Specification of Letters Patent.

Patented May 7, 1907.

Application filed March 8, 1905. Serial No. 249,094.

To all whom it may concern:

Be it known that I, EDWIN E. SLICK, of Pittsburgh, Allegheny county, Pennsylvania, have invented a new and useful Method of 5 Rolling Flanged Shapes, of which the following is a full, clear, and exact description, reference being had to the accompanying drawings, forming part of this specification, in which—

10 Figures 1 and 2 show the successive passes arranged in accordance with my invention in two three-high mills, and Fig. 3 is a view similar to Fig. 2 showing a different arrangement of the finishing passes.

15 My invention relates to the rolling of shapes having wide flanges, and is designed to produce such shapes without the use of universal mills.

In the drawing, Figure 1 shows a three-high 20 mill having rolls 2, 3, and 4, and containing five passes. I start with a bloom or billet, which in passing through the first pass *a* is provided with the longer diagonally opposite flanges 5 and 6 and with the shorter rudimentary flanges 7 and 8. The metal then returns through the pass *b*, in which the flanges 25 7 and 8 are elongated and the flanges 5 and 6 are contained in the dead groove, and hence not elongated. It will be noted that the flanges 5 and 6 which are in the live groove in the first pass are in the dead groove in the second pass. It will also be seen that the live grooves are formed by substantially flat faces which taper or converge toward each 30 other outwardly with an open space at the end of the pass. The live grooves therefore are always open, and the dead grooves always closed; and by making the faces of the live grooves substantially flat and outwardly 35 converging, I obtain the very substantial elongating of two of the flanges. In the third pass *c* the flanges 5 and 6 are within the live grooves and are therefore elongated while the flanges 7 and 8 are within the dead 40 grooves and are not elongated. In the next pass *d* the flanges 7 and 8 are elongated in the live open grooves, while the flanges 5 and 6 are within the closed dead grooves. In the fifth pass *e* the flanges 5 and 6 are elongated 45 in the open live grooves, while the flanges 7 and 8 are within the dead grooves. In the pass *f* of the second set of rolls 9, 10 and 11, the flanges 7 and 8 are elongated and made thinner in the live grooves, while the flanges 50 5 and 6 are within the dead grooves. In this the sixth pass, the flanged shape, which

in this case is a wide flanged I-beam, is brought substantially to its final dimensions, but the flanges are inclined outwardly in opposite directions. The next pass or passes 60 are merely bending passes which bend the flanges into parallel planes to form the I-beam. In the seventh pass *g* the web 12 is substantially horizontal, and the upper flanges 6 and 7 are bent into proper position, 65 while the lower flanges 5 and 8 remain bent outwardly. In the final eighth pass *h*, the web 12 is horizontal, and the lower flanges 5 and 8 are bent into planes at right angles to the web, thereby finishing the beam. In 70 this second set of rolls I have shown supplemental passes *g'* and *h'*, so that the metal may be passed through either *g* or *g'* in the seventh pass and either *h* or *h'* in the eighth pass.

75 It will be noted that in the bending pass or passes the web is supported by the rolls at the same time that the flanges are being bent to form. This is an important feature of my invention, since it prevents buckling of the 80 web and insures a good product. It will also be noted that in all of the reducing passes the web is at an angle to the axis of the rolls, this angle being reversed in successive passes.

In the modified passes of Fig. 3 the sixth 85 pass *f*^x is the same as the pass *f* of Fig. 2, but in the first bending pass *g*^x the web 12' is not horizontal, but is inclined, and none of the flanges are bent into final position in this pass. All of the flanges are bent toward 90 their final position, and then in the final pass *h*^x the web 12' is horizontal and the flanges 5', 6', 7' and 8' are bent to final position. In this case, as in the first form, the web is supported by the rolls at the same time that the 95 flanges are being bent into their final position. There is also no turning of the blank to a position at right angles to the previous pass. It will be noted that this is the case with all the passes.

100 The advantages of my invention result from the obtaining of shapes having wide flanges by means of ordinary mills other than universal mills having horizontal and vertical rolls. By arranging the diagonally opposite flanges where such are present, alternately in the dead and live grooves, and by shaping the live grooves in the manner above described, I can obtain much wider and thinner flanges 105 than have heretofore been gotten by the use of ordinary mills. The bending of the flanged shape in passes which support the 110

web is also of importance, as this prevents distortion of the web and insures a good product. It also avoids the necessity for turning the blank to an angle at 90° to the previous pass. Instead of passing any flange alternately through a live groove and then through a dead groove at each successive pass, the flange may be passed through two live grooves before entering a dead groove or two dead grooves before entering a live groove. This might be done where the mill would not permit a heavy draft, or for other reasons, and I intend to cover such variation in my claims.

15 Variations may be made in the mill or mills employed, in the contour of the flanged shape being rolled, in the number and width of the flanges, &c., without departing from my invention.

20 I claim:

1. The method of rolling wide flanged shapes, consisting in passing metal through successive separate passes, in which the web is at successively opposite angles to the axes 25 of the rolls, passing the flange portions alternately through an open live groove, and drawing out the flange between tapering substantially flat opposing faces, and then through a dead groove, and then bending the 30 flanges to final position; substantially as described.

2. The method of rolling shapes having wide flanges, consisting in feeding the metal through a series of separate passes in which 35 the web is inclined alternately at opposite angles to the axes of the rolls, rolling the flanges alternately within open live grooves and dead grooves, drawing out the flange in the open live groove to any width to which 40 the metal will flow, and then passing such flange through a dead groove; substantially as described.

3. The method of rolling flanged shapes, consisting in passing metal through successive passes, in which the web is at an angle 45 to the axes of the rolls, passing the flange portions alternately through an open live groove, and drawing out the flange therein between tapering opposing faces, and then 50 through a dead groove, and then bending the flanges to final position and finishing the shape; substantially as described.

4. The method of rolling flanged shapes of general I-beam form, consisting in passing 55 metal through successive passes in which the web is at an angle to the axes of the rolls, passing the flange portions alternately through diagonally opposite open live grooves and drawing out the flanges therein between 60 tapering opposing faces, and then passing them through diagonally opposite dead grooves, and then bending the flanges to

final position while keeping the same surface of the shape uppermost in all of the passes; substantially as described.

5. The method of rolling flanged shapes, consisting of forming the shape by rolling it with the flanges out of normal angular relation to the web, and then feeding the shape through a rolling pass or passes with at least 65 one of the flanges in a dead groove, and bending the flanges to normal position therein, while supporting the web throughout the bending operation, and keeping the same surface of the shape uppermost in all the 70 passes; substantially as described.

6. The method of rolling a shape having at least two flanges, consisting in passing the flange portions alternately through an open 75 live groove and drawing out the flange between tapering opposing faces, and then through a dead groove, with the web at an angle to the roll axes, and then bending the flanges to final position with the upper surface of the shape in the first pass the upper 80 surface in all of the passes; substantially as described.

7. The method of rolling shapes having wide flanges, consisting in feeding the metal through a series of separate passes in which 85 the web is inclined alternately at opposite angles to the axes of the rolls, rolling the pair of diagonally opposite flanges alternately within open live grooves and dead grooves drawing out the flange in the open live 90 groove to any width to which the metal will flow and then passing such flange through a dead groove; substantially as described.

8. The method of rolling I-beams, consisting in rolling the shape with its diagonally opposite flanges bent out of normal position to the web, and then rolling and bending the flanges to normal position while supporting the web by contact with the rolls in each 100 pass, and keeping the same surface of the 105 shape uppermost in all the passes; substantially as described.

9. The method of rolling flanged shapes, consisting in forming a blank having a web with flanges bent out of proper position relative thereto, rolling said blank with the web at an angle to the horizontal and then passing the blank through at least one bending pass in which the web is parallel with the axes 110 of the rolls while the flanges are being bent, and supporting the web throughout the rolling and bending operations; substantially as 115 described.

In testimony whereof, I have hereunto set my hand.

EDWIN E. SLICK.
